UNITED STATES PATENT OFFICE.

CHARLES J. GADD, OF LEBANON, PENNSYLVANIA.

RAILWAY-TRACK FASTENING.

1,024,127

Specification of Letters Patent. Patented Apr. 23, 1912.

Application filed August 29, 1911. Serial No. 646,635.

To all whom it may concern:

Be it known that I, CHARLES J. GADD, a subject of the King of Great Britain, and a resident of Lebanon, in the county of Lebanon, and state of Pennsylvania, have invented certain new and useful Improvements in Railway - Track Fastenings, of which the following is a specification.

My invention relates to an improved railway track fastening and it consists in a ball and socket arrangement of screw-spike and washer whereby the former, no matter at what angle it may be driven in the tie, will have a full bearing in the latter thus giving equal distribution of pressure over the latter where it is in contact with the rail flange.

Screw-spikes are ordinarily made with a solid head, the taper of the head being forged so as to conform to the taper of the flange of the rail which, in American practice, is commonly 13 degrees. The spike is screwed into the timber tie, passing through a tie-plate, if the tie-plate construction is used, until the cone head lies on the flange of the rail. If the spike be driven at right angles to the flange of the rail there will be a line bearing between the spike head and the flange of the rail. Outside of this bearing the head is unsupported and the shank of the spike is subjected to bending, which, not infrequently, results in breakage. If the screw be driven slightly out of the perpendicular, that is not at right angles to the rail flange, the cone head will not match up with the tapered surface of the flange and a point instead of a line bearing will be had. In my arrangement the washer is made so as to bear against both the rail flange and tie-plate, or the tie if a tie-plate be not used, it is drilled so as to allow ample play for the shank of the spike and is furnished upon its top with a concave spherical depression to receive the convex spherical portion of the spike.

In my arrangement, no matter at what angle the spike be driven in the tie, the spherical convex head of the spike will have a full bearing in the washer and the latter, owing to its peculiar construction, will not only fully support the spike but will so engage the rail flange as to obtain the best holding effect.

In the accompanying drawings, in which similar numerals of reference indicate similar parts throughout the several views; Fig-

ure 1, shows my improved screw-spike and washer, the latter in section, in place on a rail flange which is carried by a shoulder tie-plate. Fig. 2, shows the same arrangement in connection with a straight tie-plate; Fig. 3, the same arrangement in connection with a beveled tie-plate. Fig. 4, a top plan view of the washer; Fig. 5, a front elevation of the washer.

6 is the flange of a railway rail. 7 a tie-plate of any of the well known constructions, three forms being illustrated in the drawings.

8 is a washer the inner part 9 of which is beveled so as to rest upon the top of the flange 6 of the rail and the outer part 10 of which, when the inner part 9 engages the flange 6 of the rail, is adapted to rest upon the top of a tie or tie-plate as shown in the drawings. In order than an uneven surface upon the top of the tie or tie-plate may not thrust the washer out of alignment the lower end of the part 10 of the washer which engages the tie or tie-plate is curved as shown in Fig. 5, so as to have a bearing at one point only. 11, Figs. 2 3 and 4, are shoulders formed upon the under side of the washer 8, beneath and, as the device is shown in the drawings, to the left of the inner part 9 of the washer which engage the outer side of the rail flange 6 and prevent the washer turning.

In the case of a shouldered tie-plate the washer is formed to fit up to the shoulder as shown in Fig. 1.

12 is a spherical depression formed in the top of the washer 8 and 13 a hole for the passage of the screw-spike.

14 is the screw-spike furnished with the usual threads 15 and angular head 16 for engagement of a wrench.

17 is the head of the spike the under portion of which has a ball form corresponding with the spherical socket 12 in the washer 8.

As has been before stated the hole 13 in the washer 8 is large enough to give considerable clearance to the spike 14 and it will be seen that the washer 8 once being properly placed that the spherical head of the screw 14 will, when the screw is fully seated, exert the same downward pressure upon the washer, or substantially the same pressure, whether the screw be driven directly at right angles to the base of the rail or whether it be driven at an angle thereto. In any event the washer will have an even

and full bearing upon the top of the flange of the rail and there will be no tendency to bend the spike.

Having thus described my invention I claim as new and desire to secure by Letters Patent:-

1. In combination, a screw-spike the under side of the head of which is spherical in form and a washer having a spherical seat adapted to receive the spherical head of the spike and a hole through which the screw spike shank may pass.

2. In combination, a screw-spike the under side of the head of which is spherical and a washer having a spherical seat adapted to receive the spherical head of the spike and a hole concentric with said seat through which said spike may pass, the inner under side of said washer being adapted to engage the top side of the flange of a rail.

3. In combination, a screw-spike, the under side of the head of which is spherical, and a washer having a spherical seat and a hole concentric with said seat, the inner underside of said washer being adapted to engage the top of the flange of a rail, the

front of said washer having a convex bottom adapted to rest upon a tie or tie-plate.

4. In combination, a screw-spike the under side of the head of which is spherical, and a washer having a spherical seat for the head and a hole for the shank of said spike, a tapered underside to engage the top of the flange of a rail, the front of said washer having a convex bottom adapted to rest upon a tie or tie-plate, said washer having shoulders to engage the side of the rail flange.

5. In combination, a screw-spike the under side of the head of which is spherical, a washer having a spherical seat for said head and a hole concentric with said seat for the shank of said spike, the under inner side of said washer being tapered to engage the top of the flange of a rail and having shoulders to engage shoulders on the plates, the front of said washer having a convex bottom to rest upon the tie plate.

CHARLES J. GADD.
